DISK ROLLING MACHINE

John F. Reimer, Fowler, Kans.

Application January 26, 1948, Serial No. 4,448

2 Claims. (Cl. 76—89.2)

1

My invention relates to an improvement in disc rolling machines for sharpening plow discs.

The object of my invention is to provide a power driven machine of the kind mentioned that will roll the edge portion of a disc to a sharp edge.

A further object is to provide a machine of the kind mentioned that is simple, easy to make, one that will correctly receive and sharpen any standard size disc.

A still further object is to provide a machine of the kind mentioned that will quickly and efficiently do the desired job of sharpening a disc.

A still further object is to provide a machine of the kind mentioned in which one of the rollers can be slightly shifted to increase or decrease the degree of cup that may be imparted to the disc as the disc is rolled.

A still further object of the invention is to provide a machine of the kind mentioned which in its process of sharpening the disc will slightly mash the metal of the disc and thereby to some degree increase the density of the metal of the disc and therefore have a hardening effect on the metal of the disc which will cause the disc to retain its sharpness through a longer period of use.

These and other objects will be more fully explained as this description progresses.

Now referring to the accompanying drawings in which similar numerals of reference designate the same parts throughout the several figures of the drawings.

Fig. 1 is a side view of the machine.

Fig. 2 is a longitudinal and vertical detail sectional view through the machine, the view being as seen from the line II—II in Fig. 3 and looking in the direction of the arrows.

Fig. 3 is a top plan view of the machine.

Fig. 4 is a bottom plan view of the machine.

Fig. 5 is a rear end view of the machine.

Fig. 6 is a front end view of the machine.

Fig. 7 is a cross sectional detail view through the machine, the view being as seen from the line VII—VII in Fig. 2 and looking in the direction of the arrows.

The machine consists of a housing H having end walls 10 and 11, and side walls 12 and 13, and a top 14, all of which are integral with their adjacent members to form a one piece housing H at the bottom of the housing H and across the inside corners thereof are web members 15 that are integral with their adjacent end and side wall members of the housing H.

Each web member 15 has a hole 16 therethrough, through which a bolt 17 may be passed as a means of rigidly attaching the housing H to

any suitable bench or support 18 for the machine.

Rigidly mounted on the top plate 14 of the housing H is a pair of L-shaped members 19 and 20, the vertical legs of which each have holes 21 and 22 that are in alignment with each other and in which is seated the ends of a tubular bearing sleeve 23, the end portions of which are welded to their respective L-shaped supporting elements 19 and 20.

5 A shaft 24 is revolvably carried in the bearing sleeve 23, and the front end of the shaft 24 is provided with a washer 25 thereon that bears against the front face of the angle support element 20 and a pin 26 passes through the shaft 24 as a means of retaining the washer 25 on the shaft 24 and for denying rearwardly end movement of the shaft 24 is provided with a sprocket wheel 27 and preferably a multiple V belt pulley 28, both of which are rigidly attached to the shaft 24 by means of keys 29 and 30 and a nut 31 that is threaded on the extreme rear end of the shaft 24, the sprocket wheel 27 and V belt pulley 28 being positioned in rear of the rear wall 10 of the housing H.

10 The machine is provided with a roller carrying shaft 32 that extends through the upper central portion of the housing H and substantially in parallelism with the drive shaft 24. The rear end of the shaft 32 is revolvably carried in a bearing element 33 that is rather loosely fitted in an opening in the rear wall 10 and projects forwardly into the cavity of the housing H and is positioned between a pair of forwardly extending guide plates 34 and 35, the rear edges of the guide plates 34 and 35 being either welded to, or the guide plates 34 and 35 may be integrally formed on the rear wall 10 of the housing H.

15 The outside shape of the bearing 33 is square so as to fit between the guide plates 34 and 35 to prevent the bearing from revolving with the shaft 32. The bearing 33 is made as a split bearing which is held together in adjusted position around the shaft 32 by means of bolts 36 and 37 that pass through ears 38 and 39 that are integrally formed on both halves of the bearing 33.

20 Immediately in front of the bearing 33 is a spur gear 40 that is pressed thereon and is rigidly held against rotation thereon by means of a key 41 that extends into both the shaft 32 and the hub portion of the gear 40.

25 The front end of the shaft 32 is provided with a bearing element 42 that is tightly pressed on the shaft 32 and is provided with outwardly extending annular ribs 43 that are spaced apart and are integrally formed thereon.

The ribbed bearing 42 is revolvably carried in an annular grooved bearing block 44 in which the bearing 42 and ribs 43 are revolvably received and positioned. The bearing block 44 is provided with an upwardly extending tongue portion 44a that passes through an elongated opening 45 in the top plate 14 of the housing H so that the bearing 44 can be moved back and forth longitudinally with respect to the housing H and carry the shaft 32 with it for adjustment purposes that will later be described.

The upper end of the bearing portion 44a is provided with a plurality of upwardly extending ribs or tooth like elements 46 that are snugly received between other ribbed or tooth like elements 47 that are integrally formed on the underside of an adjustment bar 48 that rests on and bears against the upper surface of the top plate 14 of the housing H.

The outer ends of the adjustment bar 48 are provided with elongated holes 49 and 50 through which cap screws 51 and 52 are threaded into the top plate 14 of the housing H to rigidly bind and hold the adjustment bar 48 and the bearing 44 and shaft 32 in longitudinal adjusted positions with respect to the housing H. The front end of the bearing 44 is made square and slidably passes through a vertically positioned elongated opening 11a in the front wall 11 of the housing H and is vertically movable for a short distance therein. Across the front end of the housing H and resting against the upper surface of the upper housing plate 14 is positioned a reinforcement bar 53 that is rigidly bolted to the housing H by means of bolts 54 and 55 that pass through the upper housing plate 14 and the ends of the reinforcement bar 53 as shown. An adjusting screw 56 is threadedly passed through the reinforcing bar 53 and the upper plate 14 of the housing H so that the lower end of the screw 56 bears against the upper side of the bearing block 44 so as to hold the bearing block 44 in vertically adjusted positions. The upper end of the screw 56 projects above the reinforcement bar 53 and is made square so that a crank wrench 56a may be placed thereon by which the screw may be turned for adjustment purposes as will readily be understood.

The outer end of the shaft 32 is slightly tapered and a round edged roller 57 is tightly fitted thereon and a presser plate 58 is also positioned around the front end of the shaft 32, and a nut 59 is threaded on the outer end of the shaft 32 and bears against the presser plate 58 which in turn presses against the roller 57 to still more tightly press and hold the roller 57 on the tapered end of the shaft 32.

The shaft 32 is provided with an axial bore 60 that extends inwardly from the front end of the shaft 32 and well past the rear end of the ribbed bearing sleeve 42, and laterally extending holes 61 are drilled between the bearing ribs 43 and extend through the bearing sleeve 42 and the shaft 32 and open into the bore 60 of the shaft 32.

An oil receiving element 62, commonly known as a "jerk oiler" is threaded into the front end of the bore 60 in the shaft 32 whereby oil may be forced through the oiler 62 into the bore 60 and through the lateral passages 61 to lubricate the bearing as will readily be understood.

The machine is provided with a second roller carrying shaft 63, the rear end of which is removably carried in a bearing block 64 that is made the same, and has the same characteristics and is mounted in the rear end plate 10 of the housing 75 with an ear like formation 86 that is positioned

H and is positioned between the guide plates 34 and 35 the same as the bearing 33 and is positioned directly below the bearing 33 immediately in front of the bearing 64 and rigidly mounted on the shaft 63 is a second spur gear 65 that is in mesh with, and is the same diameter as the spur gear 40 on the shaft 32. The front end of the shaft 32 is provided with a bearing sleeve 66 that is pressed on the shaft 63. The bearing sleeve 66 is provided with outwardly extending and spaced apart annular rib portions 67 that are revolvably received in grooves in the bearing block 68, the outer portion of which is made square and is positioned in and is movable longitudinally in the lower portion of the aforementioned elongated opening 11a and bears on the front plate 11 of the housing H.

The lower portion of the lower bearing block 68 is provided with a recess 69 therein in which is positioned a cam 70 that engages the sides of the recess 69 for longitudinal movement of the bearing blocks 68. The cam 70 is preferably integrally formed on the shaft 71 the ends of which are journaled in the side walls 11 and 12 of the housing H. One end of the shaft 71 is provided with a long lever element 72, one end of which is keyed to the shaft 71 and the other end of which is formed into a handle formation 72a, the lever 72 being rockable along the outer face of the side wall 12 of the housing H.

The side wall 12 of the housing H is provided with an arcuate lock bar 73 that is spaced away from the side wall 12 and is supported by the side wall 12, and passes over the lever 72. The lock bar 73 is provided with an arcuate slot 74 therein that is centered about the center axis of the cam shaft 71. The lever 72 is provided with a cap screw 75 that is threaded thereinto and passes through the arcuate slot 74 so that the head of the screw 75 will bear against the lock bar 73 to pull and bind the lever 72 against the lock bar 73 in any of its adjusted positions.

The front bearing blocks 44 and 68 are slidably positioned between a pair of guide elements 76 and 77 that are welded to or integrally formed on the inside of the front end wall 11 and on opposite sides of the elongated opening 11a.

The front end of the lower shaft 63 is tapered and a round edged roller element 78, which is a duplicate of the roller 57 is tightly fitted on the taper of the shaft 63, and a presser plate 79 which is a duplicate of the presser plate 58 is also positioned on the outer end of the shaft 63 and bears against the roller 78, and a nut 80 is threaded on the outer end of the shaft 63 and bears against the roller 78 and a nut 80 is threaded on the outer end of the shaft 63 and bears against the presser plate 79 which in turn presses against the roller 78 to effect a further tightening of the roller on the tapered end of the shaft 63. The rear end of the shaft 63 is provided with a sprocket wheel 81 that is rigidly mounted thereon and is in alignment with the sprocket wheel 27 that is rigidly mounted on the drive shaft 24.

The machine is provided with a chain 82 that passes around and engages both sprocket wheels 27 and 81 for driving purposes as will be readily understood.

The lower central portion of the front end wall 11 of the housing H is provided with a pair of outwardly extending ear like elements 83 and 84 that are rigidly attached to, preferably welded to, or integrally formed on the end plate 11.

The machine is provided with a work support holder rod 85 the rear end of which is provided with an ear like formation 86 that is positioned

between the ear like elements 84 and 83 on the front wall 11 of the housing H and is pivotally carried on a bolt 87 which passes through the ear like elements 83-86-84.

The work support rod 85 is provided with an inverted T-shaped bracket 88 that has a bore through the head thereof and is slidably mounted on the work support holder rod 85. The other leg of the T bracket 88 is provided with a bore that is internally threaded and in which is received the threaded lower end of a work support rod 89. The upper end of the work support rod 89 is provided with a collar 90 that is slidably carried thereon and which is stationable thereon by means of a set screw 91 that is threaded through the collar and the inner end thereof will engage the work support rod 89 to rigidly bind and hold the collar 90 at any adjusted position up or down the work support rod 89.

The work support holder rod 85 is threaded to receive a wing nut 92 that is threaded thereon and bears against one end of the head of the inverted T-shaped bracket 88 to move the bracket 88 along its supporting rod 85 for adjustment purposes as will later be described.

The head of the T-shaped bracket 88 is provided with an adjustment operating lever 93, one end of which is rigidly attached to, preferably integrally formed on the head of the T-shaped bracket 88, and the lever 93 extends sidewardly, downwardly and forwardly from the T-shaped bracket 88 so that the bracket 88 and work supporting rod thereon may be rocked to adjusted positions, thereby, as will later be described.

Both side walls 12 and 13 of the housing H are provided with centrally positioned openings therethrough, such as shown at 94 that the operator of the machine can reach his hand into the interior of the housing H for any reason which he might deem necessary.

The lower shaft 63 is provided with a bore 95 lateral bores 96 through the shaft 63 and bearing sleeve 66 and between the ribs 67 to receive lubrication from an oiler 97 the same as described for the shaft 32 bearing sleeve 42 and oiler 62.

The machine would be driven by any suitable power unit that would drive V belts which would also engage and drive the V belt pulley 28 to drive the machine.

To use the machine the set screw 91 would be loosened and a disk 98 to be sharpened would be positioned on and around the work support shaft 89 and the disk 98 and collar 90 would be moved up or down the work support shaft 89 to such a point that the edge of the disk can be rocked toward and entered between the rollers 57 and 78 at the proper angle to be rolled between the rollers for sharpening purposes. The disk having thus been positioned, may be rocked toward or away from the rollers 57 and 78 by raising and lowering the outer end of the work support holder shaft 85 and the work support shaft 89 may be rocked sideways to or away from a line passing through the point of tangency of the rollers 57 and 78 and running longitudinally with the machine. This movement or adjustment may be accomplished by rockably moving the outer end of the lever 93 about the shaft 85, the object of this movement or adjustment will later be made obvious.

The disk having thus been mounted, the lever 72 may be rocked or swung whereupon the cam shaft and cam thereon will be rocked to move the front bearing block 68 longitudinally to adjust the alignment or disalignment of the rollers 57 and 78, whereupon the rod 85 may be rocked up-

wardly and the disk 98 will move inwardly between the rollers 57 and 78 with the edge of the disk a little past the point of contact of the rollers 57 and 78 thereon.

5 The disk having thus been placed the screw 56 is screwed downwardly which in turn moves the upper bearing block 44, the front end of the shaft 32 and roller 57 thereon downwardly to engage the disc 98 between the two rollers which will produce very slight indentures therein, due to the pressure exerted by the rollers 57 and 78. The foregoing described movement and pressure therefrom having been achieved the cap screw 75 may be tightened and the lever 72 will be rigidly held in its adjusted position.

Now the power may be applied to the machine, whereupon the V belt pulley 28, shaft 29 and sprocket wheel 27 thereon will be revolved so that the sprocket wheel 27 will drive the chain 82 which in turn drives the sprocket wheel 61 which in turn revolves the shaft 63 and gear 65 which in turn drives the gear 40 to revolve the shaft 32 whereupon the rollers 57 and 78 are revolved and they in turn feed the disk 98 therebetween and produce a circular indenture therearound, a slight distance from the edge of the disk, and as the rollers 57 and 78 continue to revolve the disk is rolled therebetween and the lever 93 may be slightly raised, whereupon the disc supporting element 89 will be tipped slightly sideways which in turn will similarly tip the disc which will effect a spiral line of travel of the disc between the rollers and the disc will therefore eventually move outwardly until the rolling action of the rollers is directly on the edge of the disc, and as the disc travels in its movement the thickness of the disc where the rollers 57 and 78 contact the disc diminishes, therefore as the disc 98 moves outwardly the rollers 57 and 78 must be brought closer together until at the edge of the disc 98 the rollers 57 and 78 would substantially contact each other at which time the edge of the disc 98 will be rolled into an extremely sharp and hardened edge. The bringing of the rollers 57 and 78 together may be accomplished by turning the adjusting screw 56 to move the bearing block 44 downwardly whereupon the roller 57 would be similarly moved to approach or even engage the looser roller 78.

50 It may be desirable also in some cases to operate the rollers 57 and 78 slightly out of alignment with each other so as to maintain the original curvature of the disc 98 as it is being rolled. To accomplish this adjustment of the rollers 57 and 78 the cap screws 51 and 52 may be slightly loosened and the adjusting bar 48 may be slipped either forward or backward the desired distance, whereupon the upper bearing block 44 and shaft 32 will be similarly moved to effect the same movement of the upper roller 57 over the lower roller 78. The upper roller 57 having thus been adjusted, the cap screws 51 and 52 may again be tightened to rigidly hold the adjustment that was made as above described.

65 The alignment or disalignment of the rollers 57 and 78 may be adjusted to meet the desire of the operator of the machine during the progress of the rolling operation by rocking the lever 72 up or down, whereupon the shaft 71 and cam 79 thereon will be revolved and move the lower bearing block 68, shaft 63 and roller 78 thereon longitudinally to place the roller 78 in the desired relationship to the upper roller 57.

70 While the machine as shown in the drawings and described in the foregoing specification is

probably the preferred form of the machine, it is to be understood that such modifications of the machine may be employed as lie within the scope of the appended claims without departing from the spirit and intention of the invention.

Now having fully shown and described my invention, what I claim is:

1. In a disc sharpening device of the kind described, a supporting frame and a pair of roller carrying shafts, said shafts being revolvably carried in bearing blocks positioned at the ends of said shafts, said bearings being carried by said frame, a pair of rollers, said rollers being carried, one on adjacent ends of each of said shafts, and means for revolving said shafts, the bearing block adjacent one of said rollers being adjustable vertically, the bearing block adjacent the other of said rollers being adjustable longitudinally and means for carrying each of said shafts with their respective bearings as they are adjusted as aforesaid, the means for moving said shafts with their respective movable bearing blocks being outwardly extending annular rib elements rigidly carried by their respective shaft, said bearing blocks having grooves therein to revolvably receive said ribs.

2. In a disc sharpening device of the kind described, a supporting frame and a pair of roller carrying shafts, said shafts being revolvably carried in bearing blocks positioned at the ends of said shafts, said bearings being carried by said

frame, a pair of rollers, said rollers being carried, one on adjacent ends of each of said shafts, and means for revolving said shafts, the bearing block adjacent one of said rollers being adjustable vertically, the bearing block adjacent the other of said rollers being adjustable longitudinally and means for carrying each of said shafts with their respective bearings as they are adjusted as aforesaid, the means for moving said shafts with their respective movable bearing blocks being outwardly extending annular rib elements rigidly carried by their respective shaft, said bearing blocks having grooves therein to revolvably receive said ribs, and means for entering lubricating material through said shafts and between said ribs.

JOHN F. REIMER.
